PUMP FOR CHARGING TWO-STROKE
INTERNAL-COMBUSTION ENGINES

Frederick Roland Lloyd, Grimsby, England

Application May 7, 1947, Serial No. 746,441
In Great Britain July 24, 1944Section 1, Public Law 690, August 8, 1946
Patent expires July 24, 1964

2 Claims. (Cl. 103—157)

1

Two-stroke cycle internal combustion engines charged and/or scavenged by crankcase action or by means of a separate pump are known but, generally speaking, they are inefficient unless valves be employed. The object of the present invention is an improved construction of pump whereby the maximum volumetric efficiency may be obtained.

To this end, and in accordance with the invention, there is employed a double-acting pump having a combined piston and sleeve valve having both reciprocatory and oscillatory movement in a cylinder, the piston being situated midway of the length of the sleeve valve and the cylinder being closed at its ends by inwardly projecting heads to provide a close fit at the top and bottom of the piston stroke, one of the heads being apertured for the passage therethrough of a piston rod, wherein each half, upper and lower, of the sleeve valve is formed with two ports, an inlet and an outlet port, and the cylinder is formed with an inlet port midway of its height and with two angularly spaced outlet ports offset somewhat with respect to the mid-height of the cylinder.

In the accompanying drawings one form of the invention is illustrated partly in section and partly in elevation, Figure 1 being a view as seen from the right, Figure 2, and Figure 2 being a view as seen from the left, Figure 1; while Figure 3 is a cross-section on the line 3—3, Figure 1.

As shown, a double-acting charging pump for use with a twin-cylinder two-stroke internal combustion engine has a piston *a* with which is incorporated a cylindrical sleeve valve *b* mid-way of the length of which the piston *a* is situated. This combined piston and sleeve valve is slidable, with combined reciprocatory and oscillatory movement in a cylinder *c* closed at its ends by inwardly projecting heads *d*, *e*, to provide a close fit at the top and bottom of the piston stroke, the head *e* being apertured, connected with a tubular extension *f* and fitted with a gas-tight bush *g* for the passage therethrough of a piston rod *h*. Each half, upper and lower, of the sleeve valve *b* is formed with an inlet port such as *j* and an outlet port such as *k* at suitable heights and at suitable angles of displacement about its periphery. The cylinder *c* is formed with an inlet port *m* mid-way of its height and with two angularly spaced outlet ports *n*, *n*, offset somewhat with respect to the mid-height of the cylinder *c*, the one appertaining to the upper part of the cylinder *c* being a little higher than the other which appertains to the lower part thereof.

2

The two outlet ports communicate with the two cylinders of the engine with which the pump operates.

Clamped to the piston rod *h* beneath the gas-tight bush *g* and within a continuation piece *o* of the tubular extension *f* is a collar *p* carrying a radially extending pin *q* which projects into a ball *r* fitted in a spherical seating *s* eccentrically situated in needle roller bearings *t*, in a crank disc *u* on a lay shaft *v* mounted in suitable bearings *w*, *w*, in a housing *x* secured to, and projecting laterally from the continuation *o* of the tubular extension *f* and constituting therewith an oil-tight casing. The lay shaft *v* is driven by sprocket *y* and chain (not shown) or other suitable gearing by any convenient prime mover, such as the internal combustion engine to be charged, at the same rate of rotation as the engine crankshaft.

In use, and assuming the piston *a* to be at the top of its stroke, the downward turning movement of the piston gives rise to negative pressure in the upper part of the cylinder *c* until the upper inlet port such as *j* of the sleeve *b* communicates with the inlet port *m* of the cylinder *c* whereupon a charge is drawn in to said upper part. By the time the piston *a* reaches the bottom of its stroke communication between these ports *j* and *m* is cut off and the charge is trapped; and as the piston *a* rises its oscillatory movement is in the opposite direction, the upper outlet port such as *k* of the sleeve valve *b* is brought into communication with the upper outlet port *n* of the cylinder *c* and the charge is expelled. Simultaneously the same action takes place beneath the piston *a* except that the charge is drawn in when the piston is moving upwardly and, when it is moving downwardly, the charge is expelled through the lower outlet port *n* of the cylinder *c*, it being understood that although the two outlet ports *n*, *n*, of the cylinder *c* are not at the same level they may, in some instances, lead to a common pipe for delivering the charge to the internal combustion engine.

When used with a single-cylinder internal combustion engine, the capacity of the cylinder *c* of the pump should be at least equal to that of the cylinder of the engine and, if required, a supercharge of any desired value, within reason, may be obtained by increasing the diameter and/or length of the pump cylinder *c*.

If the piston rod *h* of the pump is to serve as a lubricant pump the lower end of the continuation piece *o* of the tubular extension *f* in which

the piston rod *h* is guided has a further continuation piece *z* which is arranged for connection as at 11, 12, Figures 2 and 3, with an unshown source of supply, such as the engine sump and with the lubricating conduits of the engine (not shown).

In the continuation piece *z* is a fixed sleeve 13 in which the end of the piston rod *h* slides and this sleeve 13 is formed with two longitudinally extending slots 14, 15 communicating with the connections 11 and 12 respectively.

The piston rod *h* is formed with longitudinally extending slots 16 and 17 at 180° to one another. The lower end of the piston rod *h* is bored axially as at 18 and fits slidably over a plunger 19 projecting upwards axially into the continuation piece *z*, and sleeve 13, being held in position by a cap 20 screwed on to said continuation piece *z* and clamping thereagainst a disc-shaped head 21 on the plunger 19. As the piston rod *h* reciprocates and oscillates, the slots 16, 17 come into communication, selectively with the slots 14, 15 in the sleeve 13. As the piston rod *h* rises suction occurs in that part of its bore 18 above the plunger 19 and when the slot 16 in the piston rod *h* communicates with the slot 14 in the sleeve 13 leading from the source of supply, oil rushes in and on the return stroke this oil is forced out when the slot 17 in the piston rod *h* communicates with the slot 15 in the sleeve 13 leading to the lubricating conduits. It is desirable that oil from the source of supply should flow by gravity to the pump.

If desired, the plunger 19 may have a spherical or hemispherical head instead of the disc-shaped head 21 to enable the plunger 19 to be self-aligning in the bore 18 of the piston rod *h*, the seating for such a head being formed correspondingly.

The charging effected by the pump forming the subject of this invention can be timed to suit the type of internal combustion engine with which it is to be used and full advantage can be taken of the maximum charging period of the engine. For instance the transfer port of the engine cylinder can be arranged to remain open after the exhaust port has closed, resulting in a much heavier charge being admitted to the engine cylinder and thereby increasing the volumetric efficiency of the engine.

If the pump is to be used with a single-cylinder two-stroke internal combustion engine, both the outlet ports of the pump may be coupled with a common manifold communicating with the engine cylinder, and if the swept volume of the pump is the same as that of the engine cylinder, the pump may be run at half the speed of the engine crankshaft.

The pump may be used with a four-cylinder two-stroke internal combustion engine having its four cranks set at 90° by arranging the pump to have a total swept volume equal to the total swept volume of two of the cylinders of the engine, so that two cylinders are fed from the upper outlet port *n* of the cylinder *c* and two cylinders from the lower outlet port *n*, the pump being driven at engine speed. On each stroke of the pump, two cylinders of the engine would be charged.

Where an engine has a greater number of cylinders, they may be arranged to be fed in groups from two or more pumps, e. g., for an eight-cylinder engine, two pumps could be ar-

ranged in the manner described above, each pump charging four cylinders.

I claim:

1. A double-acting pump for charging a two-stroke internal combustion engine, comprising a pump cylinder, a combined piston and sleeve valve in a pump cylinder, a piston rod for the piston, means for imparting both reciprocatory and oscillatory movement to the combined piston and sleeve valve, the piston being situated midway of the length of the sleeve valve, and inwardly projecting heads on the cylinder closing the ends thereof and providing a close fit at the top and bottom of the piston stroke, one of said heads being apertured for the passage therethrough of the piston rod, each of the upper and lower halves of the sleeve valve being formed with two ports constituting an inlet and an outlet port and the cylinder being formed with an inlet port midway of its height and with two angularly spaced outlet ports offset with respect to the mid-height of the cylinders, a lubricating pump cylinder spaced from said first mentioned pump cylinders in which an end of the piston rod remote from said first mentioned piston is reciprocatory, a fixed plunger projecting into the lubricating pump cylinder, the piston rod being formed with an axial bore to receive the fixed plunger and with longitudinal slots, a source of lubricant supply, the lubricating pump cylinder being formed with longitudinal slots arranged for connection with the source of lubricant supply and with lubricating conduits in the internal combustion engine, the longitudinal slots in the piston rod being caused to communicate selectively with the longitudinal slots in the lubricating pump cylinder in order that the piston rod may serve as a lubricant pump.

2. A lubricating pump having a fixed cylinder, a reciprocatory and oscillatory piston rod, a fixed plunger projecting into the cylinder, the piston rod being formed with an axial bore to receive the fixed plunger and being formed with longitudinal slots, a source of lubricant supply a lubricant delivery conduit, the cylinder being formed with longitudinal slots arranged for connection with the source of lubricant supply and with the conduit, the longitudinal slots in the piston rod being caused to communicate selectively with the longitudinal slots in the cylinder, and means for imparting both reciprocatory and oscillatory movement to the piston rod comprising a radially extending pin on the piston rod, a crank on a driven shaft, a ball-joint seating on the crank and a ball-joint seating, the radially extending pin projecting into said ball.
